UNITED STATES PATENT OFFICE.

CHARLES W. WILSON, OF LAWTON, OKLAHOMA.

AMUSEMENT DEVICE.

1,418,999.

Specification of Letters Patent. Patented June 6, 1922.

Application filed October 23, 1919. Serial No. 332,583.

To all whom it may concern:

Be it known that I, CHARLES W. WILSON, a citizen of the United States, residing at Lawton, in the county of Comanche and 5 State of Oklahoma, have invented certain new and useful Improvements in Amusement Devices, of which the following is a specification.

This invention relates to amusement devices, and an object of the invention is to 10 provide an amusement device wherein the passengers thereof will experience substantially the same feeling as an aviator when performing the "falling leaf" stunt in an 15 airplane.

An object of this invention is to provide 20 an amusement device comprising a rotary wheel, rotatable about an axis, which wheel has a plurality of shafts carried thereby, radiating from the axis of the wheel, which 25 shafts carry passenger carrying seats, and also to provide means for rotating these seats radially of the axis of the rotation of the wheel, so that the passengers thereof will assume various positions, during the 30 operation of the amusement device, simulating, to a material extent, the positions occupied by an aviator when looping the loop, or performing the "falling leaf".

Other objects of the invention will appear 35 in the following detailed description taken in connection with the accompanying drawings, forming a part of this specification, and in which drawings:

Figure 1 is a side elevation of the improved amusement device.

Figure 2 is an end elevation of the amusement device.

Figure 3 is a detail section through the 40 amusement device illustrating the mechanism for rotating the seat carrying shafts.

Figure 4 is a detail view illustrating one of the passenger carrying seats.

Figure 5 is a detail view partly in section 45 illustrating the mounting of the outer ends of a radial shaft and bearings carried by the rim of the rotary wheel structure.

Referring more particularly to the drawings, wherein like characters indicate like 50 and corresponding parts throughout the several views, 10 and 11 indicate the support, each comprising a base 12 and upwardly extending converging bracing arms which support bearings 13 on their upper ends.

The shaft 14 is mounted in the bearings 13,

and is keyed to one of said bearings as shown at 15, to prevent rotation of this shaft. The tubular shaft 16 is rotatably mounted upon the shaft 14, and this shaft 16 carries the wheel structure, comprising spaced annular 60 rims 17, which are connected by transversely extending braces 18. The rims 17 have spokes 19 attached thereto which connect the rims to the hollow shaft 16.

The hollow shaft 16 is connected by any 65 suitable power transmitting mechanism, such as a sprocket and sprocket chain structure 20 to a motor or analogous prime mover 21, for rotating the shaft 16 and consequently the wheel structure about the shaft 70 14 as an axis.

The shaft 16 is enlarged, intermediate its ends to form a gear casing 22, into which the inner ends of a plurality of radially extending shafts 23, project. These shafts 23 extend radially of the shaft 16, and have their outer ends journaled in bearings 24 which are carried by the transverse braces 18. The shafts 23 have bevelled gears or pinions 25, upon their ends which project into the casing 22, and these pinions mesh with the teeth of a bevelled gear 26, which is keyed upon the shaft 14, so that during the rotation of the wheel structure about the shafts 14 as an axis, the radially extending shaft 23 will 85 be rotated about axes radially of the shaft 14.

Seats 30, for carrying passengers are attached to the shafts 23, near the outer ends thereof, in such manner that the seats will 90 be rotated with the shafts 23 about their axes as well as about the common axis of the wheel structure. The seats 30 are rigidly attached to the shafts 23, so that the diametrically opposed shafts which extend vertically will have the seats thereof positioned in opposite manner, or in other words, the seats carried by the shafts 23 extending downwardly in a vertical manner from the shafts 14 will be in upright position, while the seat 30 carried by the shaft 100 23 extending upwardly in a vertical plane from the shaft 14 will be inverted, as shown in Figure 1 of the drawings, so that during rotation of the wheel structure the passengers in the seats 30 may be subjected to 105 rotary movement about the common axis of all of the seats, that is the shaft 14, and also rotary movement radially of the common axis, and about the axis of respective carrying shafts 23; imparting thereto a 110

motion similar to the motions gone through by an aviator when performing the "falling leaf" in an aeroplane, and it is readily apparent that the passengers riding in the device will experience surprising sensations during the operation thereof.

The seats 30 are preferably upholstered with soft cushions, 31, to prevent injury to the passengers of the device. Straps 32 are attached to the upholstered side of the back of the seats 30 and these straps are adapted for attachment with buckles 33, carried by the seat structure, and for extending about portions of the body of the passengers to securely strap the passengers in the seats 30 in order to eliminate any liability of accident to the passengers during operation of the amusement device.

Changes in details may be made without departing from the spirit of this invention; but,

I claim:

1. An amusement device, comprising a wheel, a supporting structure including a horizontal axis for vertical rotation of said wheel, seats radially mounted on said wheel for rotation with respect to said wheel, and means for vertically rotating said wheel, and radially rotating said seats.
2. In an amusement device, a body rotatable about a central horizontal axis, said body including a plurality of shafts radiating from said axis, seats carried by said radiating shafts, means for rotating said body, and means for rotating said shafts.
3. In an amusement device, a plurality of

shafts radiating from a common axis, passenger carrying seats rigidly carried by said radiating shafts, and means operable by rotation of said radiating shafts about said common axis for rotating them about individual axes transversely of said common axis.

4. In an amusement device, a pair of wheels adapted to rotate about a common axis, each wheel including a hub, a rim and radiating spokes, transverse braces connecting the rim portions of said wheels, a plurality of shafts radiating from said common axis and journaled in said transverse braces, seats carried by said radiating shafts, and means for rotating said radiating shafts upon rotation of the entire body upon the common axis.

5. In an amusement device, the combination, of a supporting structure, a shaft carried thereby, a hollow shaft rotatably mounted upon said first named shaft, a wheel structure carried by said hollow shaft, means for rotating said hollow shaft and wheel structure, a plurality of shafts extending radially from the axis of said wheel structure, passenger carrying seats rigidly attached to said radially extending shafts, a bevelled gear upon said rigid shaft, and bevelled pinions upon the inner ends of said radial shafts and meshing with said bevelled gear, whereby the radial shaft will be rotated about individual axes during rotation of the wheel.

CHARLES W. WILSON.
